UNITED STATES PATENT OFFICE.

THEIS F. BERNARD, OF DETROIT, MICHIGAN, ASSIGNOR TO FREDERICK M. EHEHALT,
OF DETROIT, MICHIGAN.

COMPOUND GRINDING-HEAD FOR GRINDING TWO CYLINDRICAL MACHINE PARTS AT THE SAME TIME.

1,395,790.

Specification of Letters Patent.

Patented Nov. 1, 1921.

Application filed May 17, 1920. Serial No. 382,190.

To all whom it may concern:

Be it known that I, THEIS F. BERNARD, a citizen of the United States, residing at Detroit, county of Wayne, State of Michigan, have invented certain new and useful Improvements in a Compound Grinding-Head for Grinding Two Cylindrical Machine Parts at the Same Time, and declare the following to be a full, clear, and exact description of the same, such as will enable others skilled in the art to which it pertains to make and use the same, reference being made to the accompanying drawings, which form a part of these specifications.

The objects of my invention are to provide means for adjusting and alining the double grinding spindles in the grinding head, so both are in the same plane with respect to the axis of the grinding wheel, and to provide a perfect alinement of the upper spindle with the axis of the lower spindle, and mechanical means for making these adjustments.

It is a further object of my invention to secure a rigid construction of the grinding head with accurate means for adjustment, and simple means for operating the parts. These several objects are secured in the preferred form by the construction and arrangement of the parts, as are more fully hereafter described.

Similar parts on all drawings are marked by similar numerals.

Figure 1, is a front view of the grinding machine showing the general arrangement of the working parts, supporting and operating the double grinding spindles.

Fig. 2, shows a top view of the grinder with the adjusting mechanism for bringing the spindles in alinement with the axis of the grinding wheel.

Fig. 3, is an end view showing the drive gears and means for the horizontal adjustment of the spindles.

Fig. 4, is a sectional view on the line —AA—, on Fig. 1, showing in detail, the means for both the vertical and horizontal adjustment of the head stock spindles.

Fig. 5, is a sectional view taken on the line —BB—, on Fig. 1, showing the means for both the vertical and horizontal adjustment of the tail stock spindles.

Fig. 6, is a sectional view on line —CC—, Fig. 3, showing the arrangement, adjustment and operation of the spindles relative to the axis of the grinding wheel.

I will now describe more fully the working parts, and the construction thereof, referring to the accompanying drawings and the marks thereon.

The grinding head is mounted on a swivled base plate 1, securely fastened to the horizontally moving table 2. The carriage is supported by the main base casting 3, and held in place by the grooved slides which allow a free, but rigid, horizontal movement of the table. On the bottom of the carriage base 2, is a rack 4 engaging the pinion 5. Pinion 5 is operated by the hand wheel 6 on the front of the grinder base, giving the table its horizontal movement in a plane parallel to the axis of the grinding wheel, and carrying the work pieces across the surface of the grinder. At the ends of the base plate 1, are the solid horizontal support blocks 7 and 8 rigidly attached thereto, but can be adjusted thereon, so as to care for the different lengths of work pieces held in the grinding spindles. The tops of the horizontal blocks are planed smooth with beveled edges to form a sliding support for the grinding spindle heads, with means for the horizontal adjustment of the spindles at right angles to the axis of the grinding wheel.

Mounted on the support block 7, and attached thereto by means of bevel sliding

clamps, is the vertical support block 9. By means of a screw adjusting shaft 10, mounted in the horizontal block 7, and connected to block 9 by means of a threaded nut on the bottom thereof, the vertical block 9 can be moved in a horizontal plane at right angles to the axis of the grinding wheel, thus giving the spindles in the head stock the proper adjustment to bring the work pieces in contact with the surface of the grinding wheel.

The adjusting shaft 10 is rotated by means of gear 11 mounted thereon, and meshing with gear 12. Gear 12 is mounted on, and driven by shaft 13 and hand wheel 14. Mounted on the vertical support block 9, by means of bevel sliding clamps, is the solid double spindle head 15. By means of the screw adjusting shaft 16 mounted in the

vertical support block 9, and connected to block 15 by means of a threaded nut on the side, the spindle head 15 is caused to move in a vertical plane, and adjust the spindles 5 so that both the working pieces are in contact with the surface of the grinding wheel, also to provide for the grinding of different diameters of work pieces at the same time. When the axis of the grinding wheel lies 10 half way between the two axes of the two grinding spindles, both work pieces will be ground the same size, but by raising or lowering the spindle blocks, one of the spindle centers will be placed farther from the 15 surface of the grinding wheel, thus making the work on that spindle of a larger diameter. The adjusting screw 16 is rotated by gear 17 mounted thereon and which meshes with gear 18. Gear 18 is mounted on and is rotated by shaft 19, and hand wheel 20. The 20 spindle block 15 carries mounted therein, the adjustable sleeve bearings 21, which fit tight but with a horizontal adjustment of the spindles by means of the threaded lock 25 nuts 22 at each end thereof. Inside the sleeve bearing 21, and rotating therein, are the drive spindles 23 and 24. At the outer end of the spindles 23 and 24, and securely fastened thereto, are the drive gears 25 and 30 26. Both the gears 25 and 26 mesh with a common drive gear 27, which is driven by a power pulley 28. On the inner end of the spindles 23 and 24, and mounted therein, are the center points 29, which support the work 35 pieces. Also mounted on the inner end of the spindles 23 and 24, and rotating therewith, are the face plates 30 for driving the work pieces by means of the dogs 31 connecting therewith. At the tail end of the base 40 plate 1, and mounted on the horizontal support block 8, is the vertical support block 32. Block 32 is connected to block 8 by means of bevel sliding clamps which allow it to slide in a horizontal direction on block 8. 45 Adjusting screw 33 is mounted in block 8, and connected to block 32 by means of a threaded nut at the bottom. Any turning of the screw 33 will move the block 32 in a horizontal direction on the slide. Shaft 33 is rotated by gear 34 mounted thereon. Gear 34 meshes with gear 35, which is mounted on a loose collar 36, and rotates freely on shaft 13. At the outer end of collar 36 are teeth 50 which engage in collar 37. The collar 37 is splined to shaft 13 by means of a key, and may be adjusted thereon as the tail stock 55 is adjusted to the various length of the work pieces held for grinding. When the teeth on the collars 36 and 37 are engaged, the screw shaft 33 is rotated by the turning of the shaft 13 and the hand wheel 14. The shaft 13 being connected through the gears and the screw adjusting shafts, to both the head and tail stocks, provide a simultaneous

and uniform adjustment in the horizontal 65 plane, for the grinding spindles. It also provides an accurate means for moving the work to and from the grinding wheel. If a closer adjustment is needed to bring the axis of the spindles in the proper plane 70 relative to the axis of the grinding wheel, the teeth on the collar 37 may be disengaged from the collar 36 by sliding on the key, allowing a free movement of collar 36, and gear 34, independent of the shaft, causing 75 the proper adjustment of the support block 32, and bringing the spindles in line. Mounted on block 32 by means of sliding bevel clamps, is a single spindle bearing 38. Screw shaft 39 is mounted in block 32 and 80 is rotated by gear 40 mounted thereon. Gear 40 meshes with gear 41. Gear 41 is splined to the shaft 19 by means of a sliding key to allow for the adjustment of the tail stock. Shaft 19 being connected directly to the 85 spindle bearing blocks on both the head and tail stocks, by means of gears and the adjusting shafts, provide a simultaneous and uniform adjustment of the spindles in a 90 vertical plane, for raising and lowering the spindles to the desired position relative to the grinding wheel. Mounted on the spindle bearing block 38, by means of bevel sliding clamps, is a secondary adjustable bearing block 42 for the upper tail spindle. 95 Block 42 is held in position by means of set screws 43 and 44, any adjustment of which causes a movement of the block in a horizontal plane, and provides means for bringing the axis of the upper spindle in true 100 alinement with that of the lower spindle, to avoid taper in either the upper or lower work piece. Both the bearing blocks 38 and 42, carry a support sleeve 45 which slides endwise in the bearing. Sleeves 45 carry at the inner end a tail center point 46, to support the turning work pieces. Inside of sleeve 45 is a support coil spring 47, held in place by a stationary block 48. Block 48 is held in position by a pin passing through the slots in the sleeve 45 and into the main bearing blocks 38 and 42. At the outer end of the bearing blocks 38 and 42, are the release levers 49 and 50, which engage a notch 115 at the end of sleeve 45. Lever 50 is connected with the foot lever 51 by means of a rod 52. Any pressure downward of the foot lever 51, will rock the arm 49 and draw the sleeve 45 back and release the tail center point from the work pieces.

I do not wish to confine myself to the exact construction as herein described, but merely give this as a preferred form of construction.

Having fully described my invention herein, what I claim as my invention and desire to secure by Letters Patent is:

1. A compound grinding head with two

- pairs of work supporting spindles for holding and grinding two cylindrical machine parts at the same time, in combination with the horizontal table of the grinding machine, 65
 5 and the rotating grinding wheel positioned so as to simultaneously act on both the work pieces, a head stock, and a tail stock to support the spindles, a horizontal sliding plane splined to the spindle supports, a screw for
 10 making a horizontal adjustment of the same to bring the work to and from the grinding wheel.
2. A compound grinding head with two pairs of work supporting spindles, in combination with the horizontal table of the grinding machine, and the rotating grinding wheel mounted thereon, positioned so as to simultaneously act on both the work pieces, a head and tail stock to support the spindles, a horizontal sliding plane splined to the spindle blocks, a screw for making a horizontal adjustment of the same, a vertical sliding plane splined to the spindle blocks, and a screw for making the vertical adjustment of the 70
 20 spindles so as to adjust both work pieces to the surface of the grinding wheel to grind pieces of the same diameter or of different diameters.
3. A compound grinding head with two pairs of work supporting spindles, in combination with the horizontal table of the grinding machine, and the rotating grinding wheel mounted thereon and positioned so as to simultaneously act on both work pieces, 75
 30 a head stock and tail stock to support the spindles, means for making the horizontal adjustment of the double spindle bearings, means for making the vertical adjustment of the double spindle bearings, and means for a secondary adjustment for one of the tail spindles so as to bring both spindles in perfect alinement.
4. A compound grinding head with double work supporting spindles, a head and tail stock, in combination with the horizontal table of the grinding machine and the rotating grinding wheel mounted thereon, a base plate with horizontal slide supports mounted on either end, the head and tail stock sliding thereon, means for clamping the same to the slides, a screw adjusting shaft with gear attached, an adjusting drive shaft with gears mounted thereon and meshing with gears on the screw adjusting shafts and means for operating the same.
5. A compound grinding head comprising two work supporting spindles, a head and tail stock, in combination with the horizontal table of the grinding machine and the rotating grinding wheel mounted thereon, a horizontal slide support for the head stock, a vertical slide support mounted thereon, means for clamping same thereto, means for adjusting same in a horizontal plane, a double spindle bearing block, means for clamping same to the vertical slide support, and means for adjusting spindle bearing in a vertical direction.
6. A compound grinding head with two work supporting spindles, a head and tail stock, in combination with the horizontal table of the grinding machine and the rotating grinding wheel mounted thereon, means for adjusting the head stock in a horizontal plane at right angles to the axis of the grinding wheel, a double bearing block with means for clamping same to the vertical slide support, a screw adjusting shaft, and means for operating said adjustment in a vertical plane.
7. A compound grinding head with double work supporting spindles in combination with the working table of the grinding machine and the rotating grinding wheel mounted thereon, a horizontal slide support for the tail stock, a vertical slide support mounted thereon, means for clamping same, means for adjusting same in a horizontal plane and at right angles to the axis of the grinding wheel, a single spindle bearing block mounted thereon, means for clamping same to the vertical slide support, and means for adjusting same in a vertical plane.
8. A compound grinding head comprising two work supporting spindles, in combination with the horizontal table of the grinding machine and the rotating grinding wheel mounted thereon, a horizontal slide support for the tail stock, a vertical slide support mounted thereon, means for clamping same, means for adjusting same in a horizontal plane at right angles to the axis of the grinding wheel, a single spindle bearing block mounted thereon, means for supporting same, a vertical adjusting screw with drive gear attached, and means for operating said screw.
9. A compound grinding head comprising two work supporting spindles, in combination with the work table of the grinding machine and the rotating grinding wheel mounted thereon, a horizontal slide support for the tail stock, a vertical slide support mounted thereon, means for making the horizontal adjustment thereof, a single bearing block for the lower spindle mounted on the vertical slide support, a vertical adjusting screw with drive gears attached, a horizontal adjusting shaft with gears attached, said gears meshing with the drive gears on the adjusting shafts of the head and tail stock bearings, means for operating said screws thus making the vertical adjustment for both the head and tail spindles simultaneous and uniform.
10. A compound grinding head with double work supporting spindles, in combination with the horizontal table of the grind-

ing machine and the rotating grinding wheel mounted thereon, means for supporting the tail stock, means for making a horizontal adjustment of same at right angles to the axis 5 of the grinding wheel, a vertical support block for the tail stock bearing, a single spindle bearing block mounted thereon, means for clamping same, a secondary adjustable bearing block for the upper tail 10 spindle mounted on top of the single bear-

ing slide, means for clamping same to slide on lower bearing block, means for adjusting same in a horizontal plane to give a perfect alignment to both spindles.

In witness whereof I, THEIS F. BERNARD, 15 sign these specifications.

THEIS F. BERNARD.
